(Cl. D26—14)

FIG. 1

FIG. 2

FIG. 3

Fig. 1 is a view, in perspective, of a coin telephone set illustrating our new design and shows the front and right sides;

Fig. 2 is an elevational view of the left side of the set; and

Fig. 3 is a rear elevational view of the set disclosed in Figs. 1 and 2.

In the various figures the dominant features of the design reside in the portions shown in full lines.

We claim:

The ornamental design for a coin telephone set, as shown and described.
